UNITED STATES PATENT OFFICE.

JAMES E. RAINWATER, OF GEORGETOWN, SOUTH CAROLINA

ADVERTISING DEVICE.

No. 845,893.

Specification of Letters Patent.

Patented March 5, 1907.

Application filed October 6, 1906. Serial No. 337,784.

To all whom it may concern:

Be it known that I, JAMES E. RAINWATER, a citizen of the United States, residing at Georgetown, in the county of Georgetown 5 and State of South Carolina, have invented a new and useful Improvement in Advertising Devices, of which the following is a specification.

This invention relates to an advertising device; and the object of the device is to display for a certain length of time a particular advertisement, to withdraw the said advertisement and substitute a new one, which is also displayed for the same length of time, 15 and to thus display in succession a number of such advertisements, finally commencing the cycle over, thus repeating the entire series as many times as desired.

The invention consists of a casing containing a traveling sheet upon which are displayed the advertisements, a continuously-operated motor, and a particular manner of gearing, whereby continuous rotation of the armature-shaft of the motor is transformed 25 into an interrupted traveling of the advertising-sheet.

In the drawings, Figure 1 is a perspective view of my device. Fig. 2 is a vertical section through the casing. Fig. 3 is a detail view showing a portion of the casing in section and the armature-shaft in cross-section, certain gearing being shown in elevation and partly in dotted lines. Figs. 4 and 5 are detail views showing, upon an enlarged scale, 35 the manner of transmitting motion to the advertising-sheet.

In constructing one of these devices I employ a casing A, which may be open upon one side, but which is preferably formed with a 40 transparent or glass side through which the advertising may be read. Upon the casing is mounted a motor A', having a shaft A², which carries a pulley A³, over which runs a belt A⁴, and this belt drives a driven pulley 45 A⁵, mounted upon a shaft A⁶, which is journaled in a side of the casing A and which upon the inner side of the casing carries a pinion A⁷. A gear-wheel B is mounted upon the inside of the casing A and is provided with a 50 continuous internal gear B' and a mutilated external gear B². A shaft C extends transversely across the casing and is provided with a sprocket-wheel C'. The pinion A⁷ meshes with the internal gear B', and the

sprocket-wheel C' engages the mutilated 55 gear B². A plurality of rollers D are arranged in the casing, and I prefer to divide these rollers into upper and lower sets, over which a traveling sheet E travels, the sheet passing alternately from a roller of one set to 65 a roller of the other set. The sheet also travels over rollers D', arranged in the upper corners of the casing, and also over the shaft C', and it will be understood that the sheet E is carried by sprocket-chains E', which run 65 over the sprockets C'. It will also be clearly understood that, while I have only shown one end portion of the shaft C, that the opposite end is a duplicate and that the sprocket C' is arranged adjacent each end. It will also be 70 obvious that idle sprockets may be employed upon any of the rollers D or D' where it is found necessary to support the sprocket-chains E', one of which is arranged adjacent each side edge of the sheet E. Suitable advertising matter of any kind may be printed or otherwise placed upon the sheet E. 75

It will be obvious from the construction shown and described that the gear-wheel B will be continuously driven, but that owing 8c to the mutilation of the gear B² the shaft C and roller E will be rotated only a portion of the time, and the mutilation of the gear B² will be such that a single advertisement will be moved into position to be read during the 85 traveling of the sheet and will remain stationary for a certain length of time, and when the sheet resumes its traveling it will move until the advertisement displayed has been entirely removed from sight and a new 90 one brought into proper position.

Having thus described my invention, what I claim as new, and desire to secure by Letters Patent, is—

An advertising device, comprising a casing, a plurality of rollers therein, a sheet adapted to travel over said rollers, a gear-wheel provided with a continuous internal gear and a mutilated external gear, a pinion meshing with the external gear, a sprocket-wheel adapted to drive said sheet and meshing with the mutilated gear, and means for continuously rotating the pinion. 95 100

JAMES E. RAINWATER.
